UNITED STATES PATENT OFFICE.

WILLIAM M. HOFFMAN, OF BUFFALO, NEW YORK, ASSIGNOR, BY MESNE ASSIGNMENTS, TO OIL FUEL ENGINEERING CORPORATION, A CORPORATION OF NEW YORK.

METHOD AND APPARATUS FOR BURNING HYDROCARBONS.

Application filed July 16, 1921. Serial No. 485,193.

To all whom it may concern:

Be it known that I, WILLIAM M. HOFFMAN, a citizen of the United States, residing at Buffalo, county of Erie, State of New York, have invented a certain new and useful Improvement in Methods and Apparatus for Burning Hydrocarbons, and declare the following to be a full, clear, and exact description of the same, such as will enable others skilled in the art to which it pertains to make and use the same, reference being had to the accompanying drawings, which form a part of this specification.

My invention relates to the process and

apparatus for burning a carbonaceous mixture carrying a substantial hydrocarbon content, or, in other words, a substantially solid hydrocarbonaceous fuel, such as oil shale; coal in the form of coal dust, culm, or broken-up pieces of coal, which coal has been saturated with oil or the tarry residual matter produced in the distillation of oil. By thus saturating the carbonaceous material with oil or the residual matter from the distillation of oil, the volatile content of the coal is substantially increased and the flashing point of the fuel is lowered and it responds very satisfactorily to the treatment herein described.

The burner herein shown is a preferred form of burner designed to utilize the character of fuel above referred to, and in which burner the fuel burns in an efficient, thorough fashion.

The object of my method and the apparatus herein set forth as being particularly adaptable for the accomplishment of such method is to provide an improved method and apparatus for utilizing in a thoroughly satisfactory and efficient manner the character of fuel herein above referred to.

A source of inexpensive fuel would be coal dust or culm saturated with a mixture of the residual tarry matter resulting from oil distillation and fuel oil. I have found bituminous coal which carries a substantial per cent of volatile products when saturated with a small per cent of fuel oil and oil distillate to be a very satisfactory fuel for this type of burner.

These and other objects, together with details of construction of the apparatus, and of the various steps of the process will more fully appear from the following

description, appended claims and accompanying drawings, in which the construction of the apparatus is shown.

In the drawings:

Figure 1 is an end elevation of my burner. 60

Fig. 2 is a cross-section taken on the line 2—2 of Fig 1.

Fig. 3 is a cross-section taken on the line 3—3 of Fig. 2.

Fig. 4 is a plan view partly broken away. 65

It is thought that an understanding of my invention will be facilitated by first describing the construction of the apparatus shown in the drawings.

I provide a receptacle *a* for containing 70 fuel, built in the form of a hopper, the lower portion *b* of which is shaped to serve as a casing adapted to contain a hollow grate *c* around the exterior surface of which grate the coal contained in the casing is 75 disposed, and upon the interior surface of which grate such coal is burned.

A preferable form of grate construction is that of the hollow cylinder provided with 80 grate bars *d* which extend parallel the axis of the grate and are spaced apart from each other such a distance, that the fuel supported thereon will not pass readily therethrough into the interior of the grate but will be supported about its exterior 85 surface. This grate is suitably supported for rotation.

An end band *e* supports the grate bars at 90 one end and has a bearing in the casing wall, as shown. A spider *f* supports the opposite ends of the grate bars. This spider is secured to a hollow shaft *g* to rotate therewith, and is mounted in a circumferential bearing in the casing wall, as shown. 95

The shaft *g* is provided with a suitable bearing *g*² and is driven by means of a large gear *h* keyed to such shaft, which gear is engaged with a driving pinion *i* which pinion is keyed on a drive shaft *k*. A suitable 100 bearing for the drive shaft is indicated as *m*. Suitably supported within the hollow shaft, preferably spaced therefrom, is a nozzle *n* which leads from a source of steam supply, not shown herein, or a source of supply of 105 air under pressure if it is desired to use air, by means of which a jet of vapor can be projected coaxially into the interior of the grate toward the open end thereof. As shown in the drawing, the grate is open at 110

the end supported by the band *e*. The casting wall adjacent this open end of the grate is formed with a flaring mouth *o* through which the flame and heat of the burner are projected to be utilized as may be desired.

My method consists in supporting fuel around the exterior of this hollow grate *c* and burning the same in the interior thereof and projecting from one end into the interior 10 of the grate a steam jet. In burning fuel of this character in the ordinary manner, combustion is very imperfect and incomplete. My burner is of such a character, however, that the quantity of fuel in the 15 burner exposes a maximum surface to combustion and the constant supply of oxygen and hydrogen in the form of highly heated steam, and the heating of the mass of fuel during the combustion vaporizes the more 20 volatile portions which escape into the interior of the grate and are consumed. The remainder of the fuel breaks down due to the combustion, volatilizes and is also burned.

25 If so desired, the grate may be rotated through the means provided at the rate of speed found most desirable for the character of fuel used.

It is apparent that this particular construction of apparatus might be widely 30 varied.

What I claim is:

1. In a burner, a fuel receptacle, a hollow rotatably-mounted grate open at one 35 end positioned within said receptacle in such a manner that fuel may be disposed around the exterior grate surface, means for rotating said grate, means for projecting a vapor jet into the end of said grate opposite the 40 open end.

2. In a burner, a receptacle for containing fuel, a hollow, cylindrical, rotatably-mounted grate positioned within said receptacle in such a manner that the fuel will be disposed 45 around the exterior surface of the grate, means for rotating said grate, said grate open at one end, a steam jet projecting nozzle

zle positioned in the opposite end of said grate.

3. In a burner, the combination with an 50 outer combustion chamber in the form of a hopper terminating at the bottom in a cylindrical portion, of a hollow perforate cylindrical combustion chamber rotatably supported in the cylindrical portion of the 55 outer chamber to provide an annular fuel space between said inner and outer chambers, and means for creating a forced draft in said inner chamber.

4. In a burner, the combination with a 60 fuel chamber, of a hollow cylindrical grate revolvably supported interior said chamber to provide an annular fuel chamber around the grate, a hollow drive shaft engaging one 65 end of said grate for rotation, and means for projecting a vapor jet through said shaft into said grate.

5. In a burner, the combination with a fuel chamber, of a hollow perforate cylindrical combustion chamber revolvably supported within said fuel chamber to provide a fuel space therearound interior the fuel chamber, a hollow drive shaft engaging one 70 end of said combustion chamber for rotation, and a tubular jet extending through said 75 hollow shaft to project a vapor jet into said combustion chamber.

6. In a burner, the combination with a fuel chamber having a fuel inlet and an opening for the discharge of products of 80 combustion, of a hollow grate comprising a plurality of spaced-apart longitudinally-extending grate bars, which grate is positioned interior said fuel chamber to provide a fuel space around the grate within the 85 chamber, said grate open at one end to discharge products of combustion through the discharge opening of the fuel chamber, and means for projecting a vapor jet into said 90 grate from the opposite end.

In testimony whereof, I sign this specification.

WILLIAM M. HOFFMAN.
